UNITED STATES PATENT OFFICE.

LEWIS E. FAGAN, OF MINNEAPOLIS, MINNESOTA

HEAD FOR AUTOMATIC FIRE-EXTINGUISHERS.

No. 882,629.

Specification of Letters Patent. Patented March 24, 1908.

Application filed April 29, 1907. Serial No. 370,807.

To all whom it may concern:

Be it known that I, LEWIS E. FAGAN, a citizen of the United States, residing at Minneapolis, in the county of Hennepin and State of Minnesota, have invented certain new and useful Improved Heads for Automatic Fire-Extinguishers, of which the following is a specification.

My invention relates to automatic fire-extinguisher systems, and particularly to the devices for preventing the escape of the fluid until the devices are made to operate by the effects of heat.

The object of the invention is to increase the efficiency and durability of the device by providing an operating mechanism composed of resilient non-corrosive metal and do away with casings or pockets in which dirt or dust might collect and interfere with the reliability of the device. To this end I employ resilient operating devices that are restrained from action by a fusible link for holding a cap or valve on the fluid opening and which are adapted upon the fusing of the link to spring out of the way and permit the fluid to discharge.

My improvements are illustrated in the accompanying drawings, in which—

Figure 1 is a front elevation of the fire-extinguisher head, containing my improvements and showing all of the parts assembled in position to restrain the flow of the fluid; Fig. 2 is a central vertical section on the line A—A of Fig. 1; and Fig. 3 is a horizontal section on the line B—B of Fig. 1.

In the drawings 1 designates the hollow bushing through which the fluid may discharge, and which, by means of the screw-threads 2, is connected with a pipe of the distributing system; 3 is the nozzle portion of the bushing; 4 a disk thereon; and 5 a cap seated on the disk.

A link 6 of material that is fusible at a suitably low temperature engages a strip 7 of resilient metal and holds it in contact with the strut 9 that presses the cap 5 to its seat. The resilient strip 7 is secured by pins 8 to the depending resilient arms of a U-shaped

lever 10, and the arms are sprung together slightly and increase the tension exerted by 50 the strip. The frame 11 of the device is formed integrally with the bushing.

The strut 9 is somewhat pointed at both ends, the lower point seating on the cap 5 and the upper bearing against the horizontal 55 portion of the lever 10. The upper surface of the lever bears against the wedge-shaped under surface 12 of the frame.

In use, the head having been connected to a fluid pipe, when the link 6 is fused the 60 spring bar 7 is released and its resilience will throw the arms of the U-shaped lever laterally and thus free the strut and permit the fluid to lift the cap and flow from the nozzle 3. A deflector 13 on the top of the frame 65 serves to distribute the fluid.

Having described my invention, what I claim and desire to secure by Letters Patent is—

1. A sprinkler head, comprising a nozzle, a 70 cap therefor, an open frame formed on the nozzle and having a wedge-shaped inner surface opposite the nozzle, a resilient U-shaped lever the body of which bears against said wedge-shaped surface, a strut engaging said 75 cap and lever body, a spring connecting the ends of the lever arms and a fusible link for flexing said arms and spring and connecting them to the strut, substantially as set forth.

2. A sprinkler head comprising a nozzle, a 80 cap therefor, an open frame formed on the nozzle, a U-shaped lever loosely seated on said frame opposite the nozzle and having resilient arms a strut engaging said cap and lever body a spring connecting the ends of 85 the lever arms and a fusible link for flexing said arms and spring and connecting them to the strut, substantially as set forth.

In testimony whereof I have signed my name to this specification in the presence of 90 two subscribing witnesses this 25th day of April, 1907.

LEWIS E. FAGAN.
